United States Patent Office

Des. 208,787
Patented Oct. 3, 1967

208,787

EXERCISER

Anne Marie Bennstrom-Prescott, 1100 N. Alta Loma
Road, Los Angeles, Calif. 90064

Filed June 20, 1966, Ser. No. 2,739

Term of patent 14 years

(Cl. D34—5)

FIG. 1

FIG. 2

I claim:

The ornamental design for an exerciser, as shown.
